TYPEWRITING MACHINE

Lewis Cary Myers, Freeport, N. Y., assignor to
 Royal Typewriter Company, Inc., New York,
 N. Y., a corporation of New York

Application March 9, 1938, Serial No. 194,921

16 Claims. (Cl. 197—153)

This invention relates to typewriting machines, and more particularly to ribbon feeding mechanism for typewriting machines. Mechanism embodying the present invention is, however, especially adapted for the feeding of ribbons or strips of "hectograph" or other kinds of transfer medium where it is desirable to present, at the printing line, a complete new or unused portion of the transfer medium for each new line of typing, although more particularly to means for forming negative imprints on a master sheet which is subsequently used for producing numerous duplicates.

In the co-pending application of George F. Handley, Serial Number 170,451, filed October 22, 1937, there is disclosed and claimed a ribbon feeding mechanism of this general class which is operable during each return movement of the carriage to feed a length of transfer medium or ribbon equal to the length of the line typed during the preceding carriage letter space movement.

An object of the present invention is to provide a typewriter or like machine ribbon feed mechanism which will feed a length of ribbon or strip equal to the previously typed line, and in which the arrangement of parts is more compact than in mechanisms of this general character heretofore known.

Another object is to provide a mechanism of the kind referred to which is so constructed, and adapted to be so mounted on a typewriter, that none of the parts extends beyond the normal limits of the main frame to an objectionable or disadvantageous degree.

A further object is to provide such a mechanism the parts of which are adapted to be mounted mainly on the typewriter or like machine carriage.

A still further object is to provide mechanism of the character referred to and including a ribbon guiding device mounted for movement from its normal operating position to a position in which placement of the ribbon is facilitated.

Other objects will become apparent from a reading of the following description, the appended claims, and the accompanying drawings, in which:

Figure 1 is a top plan view of a typewriting machine with some parts omitted and showing mechanism embodying my invention applied thereto;

Figure 2 is a front elevation thereof;

Figure 3 is a fragmentary view in plan and on an enlarged scale showing two cooperating feeding elements with a portion of a ribbon operatively engaged thereby.

Figure 4 is a vertical sectional view taken on the line 4—4 of Figure 1 and being drawn on an enlarged scale with some parts shown in elevation;

Figure 5 is a fragmentary detail view showing a matrix or work sheet interposed between the 5 usual or conventional typewriter ribbon and a "hectograph" or other ribbon arranged to be fed in accordance with the invention;

Figure 6 is a fragmentary view in horizontal section taken on the line 6—6 of Figure 4 and 10 showing a means for freeing ribbon feed elements from operative engagement with a ribbon;

Figure 7 is a detail sectional view taken on the line 7—7 of Figure 6 and drawn on an enlarged scale;

Figure 8 is a fragmentary view in vertical section taken on the line 8—8 of Figure 1, drawn on an enlarged scale, and showing ribbon feed elements and drive mechanism therefor;

Figure 9 is a fragmentary view in vertical section taken on the line 9—9 of Figure 8 and showing a one-way drive device; and

Figure 10 is a fragmentary view in vertical section taken on the line 10—10 of Figure 8 and showing a feed roll check pawl and ratchet 25 device.

The drawings show one embodiment of the invention as applied to a Royal standard typewriting machine, but it is to be understood that mechanism embodying the invention may be 30 applied to other types of machines.

The machine shown in the drawings includes a stationary main frame A and a carriage generally designated B mounted on the main frame for reciprocatory movements in the usual manner, viz., an intermittent or step-by-step movement from right to left which is effected by a motor and an escapement mechanism actuated by the key levers or the space bar, and a return movement from left to right. Such an escapement mechanism is shown, for example, in the Patent Number 1,212,939, issued January 16, 1917, to George F. Handley.

The carriage includes the usual end plates 1 and 2 in which is journaled a platen 3, and also 45 mounted on the carriage are the usual apron 4 and rollers 5, only one of which is shown (see Figure 5), for feeding a sheet of paper C forwardly in front of the platen and thence upwardly in front of the platen. Mounted on the carriage is a bail including spaced supporting arms 6—6 connected at their forward ends by a bar 7 having journaled thereon pressure rollers 8—8 for directing usual work sheets rearwardly 50 over the platen after they have passed above the 55

- printing line. The arms 6-6 extend from the cross bar 7 rearwardly over the platen and are pivotally connected as at 9-9 to the upper ends of arms 10-10 which, in turn, are pivotally mounted as at 11 on the carriage end plates 1, 2. (See Figure 4.) Springs 12-12 interposed between the arms 6 and the carriage end plates urge the arms downwardly so as yieldably to hold the pressure rollers 8 against the platen.
- 10 Formed integrally with the end plate 1 is a laterally extending shelf 13 on which a combined line spacing and carriage return lever F is mounted and connected to the platen 3 in the usual manner. Two ribbon spools 14-14 are shown mounted on the main frame in the usual manner, the reversible inking ribbon 15 being adapted to be unwound from one of the spools 14 and wound upon the other, as is customary.
- 20 The typewriting machine as thus far described is not claimed per se as constituting the present invention, it being understood that the invention comprises parts to be hereinafter described and combinations of such parts with each other 25 and with the known typewriting machine construction already described.
- Although the invention is not necessarily restricted to the use of ribbon feed mechanism adapted to be mounted on or applied to typewriting machines of standard or known construction, it is desirable in many cases to apply the feed mechanism to such machines, and for the purposes of illustration the drawings show an embodiment which may be fitted compactly 35 to a machine of known construction without substantially increasing the over-all size of the machine and without its being necessary to alter the machine structure in any material respect.
- In the form shown, a roll ribbon supply generally designated D is mounted at the left hand end of the carriage, and the " hectograph" or other transfer medium ribbon 16 is arranged to be fed from the roll along the printing line of the platen in a manner to be described. In order to protect the master sheet C and to prevent it from being marred by the ribbon 16, a pair of spaced guards 17 is adjustably mounted on the bail bar 7, being held in adjusted position on the bar by means of screws 18, as more 50 fully explained in the co-pending application of George F. Handley, Serial Number 170,451, previously referred to.
- The ribbon supply means D includes a mounting plate 19 the major portion of which lies in a horizontal plane but which is provided with a vertical attaching flange 20 which is secured to the carriage end plate 1 by means of a nut 21 having threaded engagement with a sleeve 22 fixed to and extending outwardly to the left 60 from the carriage end plate. The sleeve 22 acts as a bearing for a platen extension shaft 23 a portion of which is shown in dotted lines in Figure 1. The shaft 23 is provided with the usual knurled knob 24 for rotating the platen. An extension bar 25 connected to the carriage end plate 1 is connected by means of a screw 26 to a vertically extending ear or flange 27 formed integrally with the mounting plate 19 for supporting the mounting plate at its outer end.
- 70 A ribbon spool 28 containing the wound-up supply of ribbon is journaled as at 29 on the mounting plate 19, a knurled nut 30 serving to hold the spool in place and to adjustably tension it against a spring friction device 31. Ribbon 16 75 is led from the spool over idlers 32 and 33 and

thence along the printing line of the platen. Preferably the idlers 32 and 33 are so mounted as to facilitate threading or placement of the ribbon, and in the form shown the idler rolls are mounted in spaced relation on a movable support or plate 34 which is pivoted to the mounting plate 19 as at 35. A spring 36 interposed between an extension 37 on the mounting plate and an ear 38 struck up from the plate 34 urges the plate to the position shown in full lines in Figure 1, 10 wherein the roller 33 is positioned to locate the ribbon 16 along and in cooperative relation to the platen 3. A stop 39 located on the mounting plate 19 is positioned to be engaged by the movable supporting plate 34 so as to limit the movement thereof under the urge of the spring 36 and properly to locate the idlers and the ribbon 16 with respect to the platen. A finger piece extension 40 which may be formed integrally with the supporting plate 34 provides for the ready movement of the supporting plate to the position shown in dotted lines in Figure 1, wherein the rollers 32 and 33 are positioned substantially in front of the platen so as to facilitate placement of the ribbon. Preferably a stop 41 is arranged to extend 25 up from the plate 19 for limiting the outward movement of the plate 34.

The support plate 34 is movable to a position to locate the idler roller 33 relatively close to the printing line of the platen for holding the ribbon 30 close to the platen, as shown in full lines in Figure 1, and is movable to another position, as shown in dotted lines in Figure 1, to locate the idler roller 33 relatively far from the printing face 35 of the platen to facilitate placing the ribbon around the idler roller. It will be observed that the support 34 is movable bodily substantially in a plane containing the platen axis and the printing line. The spring 36 is active when the support is in either of these positions for urging it 40 to the position in which the idler roller 33 is close to the printing line of the platen.

Referring now to the means generally designated E for feeding the ribbon 16, preferably there is provided a mounting bracket generally 45 designated 42 which includes a horizontal upper plate part 43 and a horizontal lower plate part 44 connected by a vertically extending plate part 45. The vertical plate part 45 is formed with an upper extension 46 secured to a stud 47 on 50 the carriage end plate 2 by means of a screw 48, and is further formed with a lower extension 49 which is secured to a stud 50 on the carriage end plate by means of a screw 51, thus firmly connecting the entire bracket 42 to the carriage. At 55 the extreme outer end of the upper plate part 43, an upturned flange 52 serves to journal a platen extension shaft 53 provided with the usual knurled knob 54.

Mounted on the bracket 42 is a pair of feed roll elements 55 and 55^a which preferably are formed with teeth or serrations normally adapted to inter-mesh and to grip between them the free end of the ribbon 16, the feed rollers being rotated in a manner to be described so as to feed the ribbon from left to right relatively to both the carriage and the main frame, as viewed in Figures 1 and 2. The feed roller 55 is secured to a shaft generally designated 56 by means of a nut 57. The shaft is formed with a relatively large central portion 58 and a relatively reduced diameter upper end portion 59 providing, between the shaft portions 58 and 59, a resultant shoulder 60, the nut 57 securely clamping the roller 55 against the shoulder so that the roller will rotate in uni- 70 75 80 85 90 95

son with the shaft (see Figure 8). The enlarged central shaft portion 58 is journaled in an aperture 61 formed in the upper plate part 43, and below the enlarged shaft portion 58 is a reduced end portion 62, a resultant shoulder 63 intervening between the shaft portions 58 and 62. A one-way drive connection or feed ratchet wheel 64 is mounted on the shaft portion 62 and is held against the shoulder 63 by means of a check ratchet 65 formed with a sleeve hub 66 extending through an aperture 67 in the lower plate part 44 and being drawn up tight by a nut 68 on the extreme lower end of the shaft portion 62. Thus the feed roll 55, the check ratchet 65, and the one-way drive or feed ratchet wheel 64 are all securely connected to and rotatable in unison with the shaft 56.

A toothed sprocket wheel element 69 is mounted on the enlarged shaft portion 58 so as to be freely rotatable with respect to the shaft. Secured to the sprocket 69 is a disc 70 which is provided with a pawl 71 pivoted to the disc at 72 and urged into engagement with the one-way drive ratchet 64 by means of a spring 73. Thus, when the sprocket 69 is rotated in a clockwise direction as viewed in Figure 9, the pawl 71 will drive the ratchet wheel 64 and consequently will rotate the shaft 56 and the feed roller 55. In order to prevent reverse rotation of the feed roller 55, a pair of check pawls 74 are pivoted as at 75 on the lower plate part 44 and are urged into engagement with the check ratchet 65 by means of springs 76, the pawls and check ratchet teeth being so disposed as to prevent counter clockwise rotation of the shaft 56 as viewed in Figures 9 and 10. Thus the arrangement is such that, when the sprocket is rotated in the clockwise direction as viewed in Figure 9 and as viewed when looking down on Figure 1, the feed roll 55 will be rotated with the sprocket, but, when the sprocket is rotated in a counter clockwise direction, the pawl 71 will ride over the teeth of the ratchet 64, and the pawls 74 will engage the teeth of the check ratchet 65 to prevent rotation of the feed roll. When the feed roll 55 is rotated in the manner just described, it will rotate the feed roller 55^a with which it intermeshes, and the ribbon 16 will be fed between the rollers from the left to the right relatively to the platen, as viewed in Figure 1.

Preferably, the feed roller 55^a is so mounted as to permit its being disengaged from the feed roller 55 so as to facilitate placing the free end of the ribbon 16 between the two feed rollers. In the form shown, the feed roller 55^a is journaled upon a shaft 77 with respect to which it is freely rotatable, and is prevented from being displaced upwardly from the shaft by means of a nut 78. The lower end of the shaft extends through a slot 79 formed in the plate part 43 and is secured as at 80 to one arm 81 of a three-armed lever generally designated 82 which is pivoted as at 83 to the plate part 43. A spring 84 interposed between an arm 85 of the three-armed lever and a stud 86 on the plate part 43 urges the lever to a position to effect operative engagement of the feed rolls 55 and 55^a. An adjustable stop screw 87 is carried by an ear 88 formed on the plate part 43, and is adapted to engage the arm 85 for limiting movement of the three-armed lever under the urge of the spring 84; and a lock nut 89 serves to lock the stop screw 87 in adjusted position. A feed roll releasing or operating lever 90 is pivoted as at 91 and is formed with a cam toe 92 engageable with

the three-armed lever for swinging the latter to the position shown in dotted lines in Figure 6 against the urge of the spring 84 for effecting disengagement of the feed rollers 55 and 55^a.

In accordance with an important feature of the invention, means adapted to be mounted on the carriage compactly is provided for operating the sprocket 69 so as to actuate the feed rolls. A flexible drive means or track, in the form shown a chain 93, is wound upon a spring actuated take-up barrel 94 journaled as at 95 on the bracket 42, a spring 96 constantly urging the barrel in "take-up" direction, that is, in a clockwise direction as viewed in Figure 1. The unwound end of the chain extends transversely to the direction of movement of the carriage along a stretch 97, and is then passed around and in operative engagement with a portion of the sprocket 69, the extreme end portion of the chain extending along a stretch 98 which is substantially parallel to the direction of carriage travel and being anchored to a bracket 99 secured to the main frame. Thus the chain engages the sprocket intermediate the take-up barrel and the connection of the unwound end of the chain to the bracket 99 on the main frame.

In operation, and with the assumption that the carriage is at the right hand end of its travel preparatory to the typing of a line, the machine will be operated in the usual manner for typing upon the master sheet C. During the typing or letter space movement of the carriage, the chain 93 will be wound up or retrieved by the barrel 94, and will travel past and effect rotation of the sprocket wheel 69 in a direction such that the pawl 71, which is rotatable in unison with the sprocket, will ride over the teeth on the ratchet 64, whereby the ratchet 64, the shaft 56, and, consequently, the feed rolls 55 and 55^a will not be rotated, and rotation of the feed rolls during the letter spacing movement of the carriage will be positively prevented by the check pawls 74 cooperating with the check ratchet 65. However, during the return movement of the carriage from left to right after the typing of a line, the chain will be unwound from or paid out by the take-up barrel so as to rotate the sprocket wheel 69 in a direction to drive the shaft 56 through the pawl 71 and the ratchet wheel 64, thereby rotating the feed rolls 55 and 55^a and feeding the ribbon 16 to the right relative to the carriage.

The gearing for driving the feed rolls is such that, during return movement of the carriage, the ribbon 16 will be fed relatively to the carriage an amount bearing a predetermined ratio to the previous letter spacing carriage movement, and, in the embodiment illustrated, the sprocket 69 is of the same effective pitch diameter as the feed roll 55, so that the ribbon 16 will be fed an amount exactly equal to the letter spacing movement of the carriage during the typing of the line just completed. In this way a completely new and unused portion of the transfer medium ribbon will be presented along the line of typing before the start of each new line, and the quality of reproduction upon the master sheet C therefore is enhanced. It will be observed that, during the letter spacing movement of the carriage, the ribbon 16 does not move relatively to the carriage, but does move relatively to the main frame, whereas, during the return movement of the carriage, the stretch of ribbon extending in front of the platen moves relatively to both the carriage and the main frame.

The typewriting machine disclosed herein em- 75

bodies the invention in a preferred form, but it will be understood that various changes may be made in the construction and relative arrangement of the parts without departing from the invention as defined in the claims.

5 I claim:

1. In a typewriting machine, the combination with a main frame of a carriage mounted thereon for movements in opposite directions and having a platen, a ribbon supply mounted on the carriage at one side of the platen, a pair of normally inactive feeding elements mounted on the carriage at the other side of the platen for engaging therebetween the free end of the ribbon and for feeding said ribbon lengthwise of and in front of the platen, and cooperating means between said feeding elements and the main frame for actuating said elements for effecting the feed of a length of the free end of the ribbon equal to the length of movement of the carriage in one direction, said means including a chain connected to said frame, a chain take-up means on the carriage, and a sprocket journaled on the carriage and meshing 20 with said chain and having driving connection with one of said feeding elements.
2. In a typewriting machine, the combination with a main frame, of a carriage mounted thereon for movements in opposite directions and having a platen, a ribbon supply mounted on the carriage at one side of the platen, a pair of normally inactive feeding elements mounted on the carriage at the other side of the platen for engaging therebetween the free end of the ribbon and for feeding said ribbon lengthwise of and in front of the platen, and cooperating means between said feeding elements and the main frame for actuating said elements for effecting the feed of a length of the free end of the ribbon equal to 30 the length of movement of the carriage in one direction, said means including a chain connected to said frame, a chain take-up means on the carriage, a sprocket journaled on the carriage and meshing with said chain, and a one-way drive connection between said sprocket and one of said feeding elements.
3. In a typewriting machine, the combination with a frame, of a carriage mounted thereon for movements in opposite directions and having a platen; means mounting a ribbon supply on the machine; a ribbon feeding device mounted on the carriage and being operable for drawing ribbon from said supply and feeding it relatively to the platen; and means for operating said feeding device during movement of the carriage in one direction comprising a take-up barrel journaled on said carriage, an elongated flexible drive member partly wound on said barrel and having its unwound end connected to the frame, and a one-way drive connection between said feeding device and the flexible drive member and engaging the latter intermediate said barrel and the connection of the flexible member to the frame.
4. In a typewriting machine, the combination with a frame of a carriage mounted thereon for movements in opposite directions and having a platen; means mounting a ribbon supply on the machine; a ribbon feeding device mounted on the carriage and being operable for drawing ribbon from said supply and feeding it relatively to the platen; and means for operating said feeding device during movement of the carriage in one direction comprising a take-up barrel journaled on said carriage, an elongated flexible drive

member partly wound on said barrel and having its unwound end connected to the frame, and one-way drive gearing between the feeding device and the flexible drive member intermediate said barrel and the connection of the flexible member to the frame, the gearing providing a gear ratio such that, upon movement of the carriage in said one direction, the feeding device will be operated to feed the ribbon relatively to the platen an amount equal to said 10 movement of the carriage.

5. In a typewriting machine, the combination with a main frame of a carriage mounted thereon for movements in opposite directions and having a platen; means mounting a ribbon supply on the carriage; a ribbon-feeding device mounted on the carriage; a one-way drive connection including a sprocket for driving said device to feed ribbon relatively to the platen; a take-up barrel journaled on the carriage; and a chain 20 partly wound upon said barrel and having its unwound end connected to said frame, the chain intermediate its frame-connected end and said barrel being in driving engagement with said sprocket.

6. In a typewriting machine, the combination with a frame of a carriage mounted thereon for movements in opposite directions and having a platen; means mounting a ribbon supply on the carriage; a ribbon-feeding device mounted on the carriage; a one-way drive connection including a sprocket for driving said device to feed ribbon relatively to the platen; a take-up barrel journaled on the carriage; and a chain partly wound upon said barrel and having its unwound end connected to said frame, the chain intermediate its frame-connected end and said barrel being in driving engagement with said sprocket, the effective pitch diameter of the sprocket being such that when the carriage is moved in one direction the feeding element will feed the ribbon relatively to the platen an amount equal to 30 said movement of the carriage.

7. In a typewriting machine, the combination with a frame, of a carriage mounted thereon for movements in opposite directions and having a platen; means mounting a ribbon supply on said carriage; two coacting feed rolls journaled on the carriage and between which the ribbon is trained; and means for driving said feed rolls during movement of the carriage in one direction for feeding the ribbon relatively to the platen comprising a sprocket connected to one of said feed rolls, a take-up barrel journaled on said carriage, and a chain partly wound on said barrel and having its unwound end connected to said frame, said chain intermediate its frame-connected end and the barrel being in driving connection with said sprocket.

8. In a typewriting machine, the combination with a frame, of a carriage mounted thereon for movements in opposite directions and having a platen; means mounting a ribbon supply on said carriage; two coacting feed rolls journaled on the carriage and between which the ribbon is trained; and means for driving said feed rolls during movement of the carriage in one direction for feeding the ribbon relatively to the platen comprising a sprocket, a one-way drive connection between said sprocket and one of said feed rolls, a take-up barrel journaled on said carriage, and a chain partly wound on said barrel and having its unwound end connected to said frame, said chain intermediate its frame-connected end and the barrel being in driving connection with said sprocket.

9. In a typewriting machine, the combination with a frame, of a carriage mounted thereon for movements in opposite directions and having a platen; means mounting a ribbon supply on said carriage; two coaxing feed rolls journaled on the carriage and between which the ribbon is trained; and means for driving said feed rolls during movement of the carriage in one direction for feeding the ribbon relatively to the platen comprising a sprocket connected to one of said feed rolls, a take-up barrel journaled on said carriage, and a chain partly wound on said barrel and having its unwound end connected to said frame, said chain intermediate its frame-connected end and the barrel being in driving connection with said sprocket, the unwound portion of said chain having a stretch extending substantially in the direction of movement of the carriage and a stretch extending substantially transverse to the direction of movement 20 of the carriage.

10. In a typewriting machine, the combination with a frame, of a carriage mounted thereon for movements in opposite directions and having a platen; means mounting a ribbon supply on the carriage at one end of the platen; a feed roll journaled on the carriage adjacent to the other end of the platen, the ribbon extending from said supply longitudinally past the platen and in contact with said feed roll and adapted to be fed at a constant ratio with respect to the feeding movement of the feed roll; and means for rotating said feed roll at a speed to feed the ribbon along the platen an amount bearing a fixed ratio to the amount of movement of the platen in one direction, said means comprising a sprocket, a one-way drive connection between said sprocket and said feed roll, a chain mounted on the carriage and being connected to the frame and having driving connection with said sprocket, 40 and means for paying out and retrieving the chain during movement of the carriage.

11. In a typewriting machine, the combination with a frame, of a carriage mounted thereon for movements in opposite directions and having a platen; means mounting a ribbon supply on the carriage; a ribbon feed device mounted on the carriage for engagement with the ribbon and adapted to always feed the ribbon relatively to the platen a predetermined amount for each predetermined amount of operating movement of the feed device; a drive chain connected to the frame; means for supporting the chain on the carriage and to yieldably tension the chain; and one-way drive means interposed between said feed device 55 and the chain including a sprocket journaled on the carriage and having meshing engagement with said chain.

12. In a typewriting machine, the combination with a frame, of a carriage mounted thereon for movements in opposite directions; a platen on said carriage; means mounting a ribbon supply, the ribbon extending from said supply longitudinally along the platen; a pair of cooperating feed rollers between which the ribbon is gripped; 60 a sprocket; a one-way drive connection between said sprocket and one of said feed rolls; a chain operatively engaging said sprocket; and means connecting said chain to said frame and said carriage and including means for paying out and retrieving said chain when the carriage is moved

on the frame in one direction to effect relative movement between the chain and the sprocket and thereby to effect rotation of the feed rolls and feeding of the ribbon by an amount bearing a predetermined ratio to the amount the platen has moved. 5

13. In a typewriting machine, the combination with a main frame; of a carriage frame including a platen and mounted for letter space and return direction movements on the main frame; a ribbon supply; and means effective upon each return of the carriage to present a fresh printed-line-length portion of the ribbon at the printing line, said means including feed rollers engaging said ribbon; a chain engaging said feed roller equipment and having one end anchored on one said frame and the other end supported on the other frame, and a sprocket connected to one of said rollers and meshing with said chain. 10 15 20

14. In a typewriting machine, the combination with a main frame; of a carriage frame including a platen and mounted for letter space and return direction movements on the main frame; a ribbon supply; and means effective upon each return of the carriage to present a fresh printed-line-length portion of the ribbon at the printing line, said means including feed rollers engaging said ribbon; a chain engaging said feed roller equipment and having one end anchored 25 on one said frame and the other end extended to and past said feed roller equipment; and means on the other frame constantly effective either to take up or to pay out the extended end of the chain accordingly as the carriage frame is moved 30 in one direction or the other, and a sprocket connected to one of said rollers and meshing with the extended end portion of the chain. 35

15. In a typewriting machine, the combination of a carriage; a platen thereon; means mounting a ribbon supply on the carriage; and means for directing ribbon from said supply along the printing line of the platen, said means including two spaced idler rollers and a support therefor mounted on the carriage for movements 40 45 towards and from the printing line substantially in a plane containing the platen axis and the printing line, in one position of the support one of said rollers being located substantially in line with the printing line of the platen and the other roller being located forwardly of said printing line, and in another position of the support both rollers being spaced substantially forwardly of the printing line of the platen. 50 55

16. In a typewriting machine, the combination with a main frame element of a carriage element mounted thereon for movements in opposite directions and having a platen; means mounting a ribbon supply on the carriage; a ribbon-feeding device mounted on the carriage; a one-way drive connection including a sprocket for driving said device to feed ribbon relatively to the platen; a take-up barrel journaled on said carriage element; and a chain partly wound upon said barrel and having its unwound end connected to said main frame element, the chain intermediate its unwound-connected end and said barrel being in driving engagement with said sprocket. 60 65 70
